UNITED STATES PATENT OFFICE.

ABE RICH, OF BIRMINGHAM, ALABAMA, ASSIGNOR TO SOUTHERN COUPON COMPANY,
A CORPORATION OF ALABAMA.

SAFETY COUPON BOOK.

Application filed August 30, 1920. Serial No. 406,758.

To all whom it may concern:

Be it known that I, ABE RICH, a citizen of the United States of America, residing at Birmingham, in the county of Jefferson and State of Alabama, have invented certain new and useful Improvements in Safety Coupon Books, of which the following is a specification.

My invention relates to a coupon book which is provided with means to prevent, without detection, the removal of coupons before the book is delivered to the customer.

Coupon books as now generally manufactured comprise a series of coupon sheets which, together with a detachable receipt stub, are bound at one end between front and back cover pages. In practice the coupon books are delivered by the agents or clerks to the party purchasing the coupon books and the receipt stub is signed and torn out and returned to the office for checking purposes. All users of coupon books have for many years been subjected to complaints from their customers on the ground that coupon books delivered to them are short a number of coupons and it has become generally recognized in this art that the use of coupon books are subject to serious objection by reason of the detachment of coupons prior to delivery of the book which is overlooked by the customer at the time of the purchase of the book. Various expedients have been attempted to prevent this fraudulent practice, but, when it is borne in mind that the low cost at which the coupon books are sold will not permit an appreciable increase in cost for obtaining this protection, the difficulty of solving the problem is at once apparent. After patient investigation

of many forms and ideas, applicant has at last produced a coupon book, the cost of which is not appreciable over that of the ordinary coupon book and which effectively safeguards the customer against the sur-reptitious detachment of coupons before the delivery of the book and which yet permits the agent delivering the book to remove the receipt stub without disturbing the means which protect the book.

Moreover, the protective measures employed are of such character as to cause the customer no appreciable inconvenience in removing them prior to the extraction of coupons and yet it is practically impossible to remove and reapply the protective

measures without noticeably defacing the coupon book and thus warning the customer.

My invention in its preferred embodiment will be best understood by reference to the accompanying drawings which form a part of this specification, and in which:

Fig. 1 shows in plan view a coupon book with my protective measures applied.

Fig. 2 is a detail view similar to Fig. 1, except that I here show a center stitch binding the leaves, and I show the stub end of the book partially torn, which must be done by the customer prior to use with it.

Fig. 3 illustrates my protective measures applied to another type of coupon book in current use.

Similar reference numerals refer to similar parts throughout the drawings.

According to my invention as illustrated, I show a coupon book consisting of a series of sheets 1 which are transversely subdivided by perforations at 2 to form individual coupons. Each coupon sheet is provided with a stub extension 3 at both ends and these extensions are separated by a line of perforations from the adjacent coupons. The stubs at both ends are bound together between a back cover 4 and a front cover 5 by suitable stitching 6, and are then covered by binding strips 7 and 8 of gummed paper, preferably of a class of paper commonly known in the trade as "kraft" paper which is not generally obtainable by the casual user and which when once applied cannot be steamed off and reapplied without distortion or defacement which serves as a warning that the book has been tampered with. The binding strips lap over and protect the stitching 6 from access.

In the drawings I have shown the binding strips as formed of kraft paper having a peculiar arrangement of lettering 9 printed thereon of non-permanent ink which will run when exposed to moisture. The strip is formed by cutting a sheet, the surface of which is printed closely with vertical columns of distinguishing data, into diagonal strips which intersect the rows at an angle so that the lettering is presented in a peculiar manner most difficult to reproduce casually, and the same type of binding strip is preferably used at both ends of the coupon book. The front and back covers are provided with lines of perforations 10 in line with the perforations in the coupon

stub adjacent to the binding strip 8. A receipt 11 is also preferably bound in at the back of the book and this sheet, as will be seen in Fig. 2, stops short of the line of perforations 10 so that its right hand end is left unbound. The purpose of this arrangement is to permit the clerk or agent to tear out the receipt leaf 11 without breaking the end fastenings and in this way the customer receives the book after the detachment of the receipt with the protective measures undisturbed. When the customer desires to use the book, it is only necessary to grasp the right hand end of the book and tear both front and back covers and the coupon stubs 3 along the lines of perforations 10, as is seen in Fig. 2.

If desired an additional protective measure may be employed consisting of a central stitch 12 formed of a frangible metal which will break if it is attempted to take it out and replace it.

In Fig. 3 I show the same idea applied to a modified type of coupon book comprising a stub 13 and a series of coupons 14 which are folded back under the stub and both the stub and the end coupon are provided with tabs 15 beyond the lines of perforations 16, which tabs are bound together by stitching 17 protected by a gummed binding strip 8 as in Fig. 1.

Having produced the protected coupon book in the manner described, if the agent of the issuing person or company attempts to remove a coupon sheet it cannot be done because if it be attempted to remove the gummed strips 7, 8 the latter will become so defaced and the ink will run so that it will be most apparent that the book has been tampered with. If the protecting strips 7 and 8 are removed they cannot be replaced except at almost prohibitive expense in view of the difficulty in obtaining the gummed paper in the first place, and secondly the impracticability of producing except at considerable cost the distinctively marked strip, because of its diagonal arrangement of printed matter thereon.

It should be borne in mind that the problem here to be dealt with is petty thievery and the full object of the invention is obtained if it becomes impractical for the casual agent to detach coupons without detection for, if one cared to go to sufficient expense in the matter, they could reproduce the coupons themselves, but inasmuch as the coupons are of small denominations and are not widely negotiable this rarely occurs. When a book is sold, if it has not the center stitch 12 the agent can spread it open, tear out the receipt 11, have it signed and deliver the coupon book, or, as is the more general practice, the company on issuing the books to the agent can remove these receipts and hold them as a check on the

agent and still deliver to the customer books that have absolutely not been tampered with. Where the center stitching is used the receipt can only be drawn out after the book has been delivered to the customer and he has torn away the end bound by the strip 8, by tearing the same along the perforated line 10, after which the stitching 12 can be readily broken loose and the receipt removed and returned to the agent.

In Fig. 3 the single coupon sheet is bound so that a coupon cannot be detached from the end of the sheet. This often occurs, the sheet being folded back between the second and third coupons and the two end coupons removed. With applicant's protective binding the customer is assured of receiving the full number of coupons and when the book is to be used he tears away the tabs 15, thereby unbinding the folded coupon sheet so that the coupons may be detached.

It is to be noted that all of the protecting arrangements are of such character as to be applied by the customary machinery and the equipment available at manufacturing plants engaged in the production of coupon books and that the additional cost of the protective measures, being all mechanically applied is negligible.

It will be understood that my invention can be variously modified without departure from the novel principles underlying it, and being the first to produce a protected coupon book, I claim all such modifications and changes as come within the general scope of my invention.

Having thus described my invention, what I claim as new and desire to secure by Letters Patent, is:—

1. A coupon book composed of sheets divided by transverse lines of perforations into end tabs and interposed suitably printed coupons, and means to provide a detachable protective binding for the end tabs comprising stitching and a gummed binding strip of paper applied over the stitching on both sides of the book and of such character as to be defaced by the application of moisture, the stitched and bound tabs and covers being adapted to be torn from the book along registering lines of perforations in the sheets to expose the coupons for detachment.

2. A coupon book composed of aligned covers and sheets, said sheets being divided by transverse lines of perforations into end tabs and interposed suitably printed coupons, perforations in the covers coplanar with the perforations in the sheets, stitching holding said covers and sheets in alignment, and a protective binding gummed strip defaceable by the moisture required to effect its removal, whereby the coupon book may be torn along the lines of the perforations.

3. A coupon book composed of perforated

coupon sheets having tabs at both ends, a receipt sheet which stops short of the tabs at one end of the book and overlaps the tabs at the other end of the book, front and back
5 covers substantially of even length with the coupon sheets, stitching to bind the sheet tabs and covers together at both ends of the book, a protective gummed strip applied over both ends of the book so as to conceal
10 and protect the stitching from being tampered with, said covers having perforations aligning with the perforations that separate from the coupon sheets the tabs at the free end of the sheets when the book is in
15 use.

4. A coupon book having the normally free ends of the leaves stitched together and provided with a gummed binding strip which covers and protects the stitching on both sides of the book and which is of such character as to be defaced by the moisture

required to effect its removal, and perforations to permit the bound ends of the leaves and covers at one end of the book to be readily torn off.

25

5. A coupon book having the normally free ends of the leaves stitched together and provided with a gummed binding strip which covers and protects the stitching on both sides of the book and which is of such character as to be defaced by the moisture required to effect its removal, and perforations to permit the bound ends of the leaves and covers at one end of the book to be readily torn off, said book having bound therein 30
35 at its other end a receipt which stops short of the said perforations.

In testimony whereof I affix my signature.

ABE RICH.
